(57) **CLAIM**

The ornamental design for an atomizer for electronic atomizing device, as shown and described.

DESCRIPTION

FIG. 1 is a perspective view of an atomizer for electronic atomizing device according to a first embodiment of my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the atomizer for electronic atomizing device that form no part of the claimed design.

The oblique shade lines in the drawings show transparency.
